UNITED STATES PATENT OFFICE.

JAMES A. BRENT, OF GRANDVIEW, WASHINGTON.

DESIGN FOR A SHOE.

57,108.

Specification for Design.

Patented Feb. 22, 1921.

Application filed May 24, 1920. Serial No. 383,997. Term of patent 14 years.

To all whom it may concern:

Be it known that I, JAMES A. BRENT, a citizen of the United States, residing at Grandview, in the county of Yakima and State of Washington, have invented a new, original, and ornamental Design for Shoes, of which the following is a specification, reference being had to the accompanying drawings, forming part thereof.

Figure 1 is a perspective view of my improved design for a shoe, showing the shoe partly unfastened.

Fig. 2 is a perspective similar to Fig. 1, showing the shoe as it would appear in use.

Fig. 3 is a partial plan view of a shoe

embodiment my new design, a portion of the upper being shown in section.

My new, original, and ornamental design comprises a shoe of a standard design which has embodied therewith two overlapping flaps at the lower ends of slits, which flaps are secured together at the outside of the shoe by a suitable clasp or clasps, the upper ends of the slit being secured by lacing, all as shown in the drawings.

I claim:

The ornamental design for a shoe, as shown and described.

JAMES A. BRENT.
